UNITED STATES PATENT OFFICE.

JOHN HOWARD ADAMS, OF MORRISTOWN, NEW JERSEY.

DESIGN FOR A GOLF-CLUB.

SPECIFICATION forming part of Design No. 27,732, dated October 12, 1897.

Application filed August 21, 1897. Serial No. 649,081. Term of patent 7 years.

To all whom it may concern:

Be it known that I, JOHN HOWARD ADAMS, a citizen of the United States, residing at Morristown, in the county of Morris and State 5 of New Jersey, have invented a new and useful Design for Golf-Clubs; and I do hereby declare that the following is a full, clear, and exact description of the same.

Reference is to be had by letters to the accompanying drawings, forming part of this specification, in which—

Figure 1 is a side view, and Fig. 2 is a perspective view, of a golf-club of my new design.

15 As shown in the drawings, the leading feature of my new design is the upwardly and rearwardly inclined face of the head of the club and the tapered rearward elongation B

of the head, having its bottom B' curved upwardly and rearwardly, and a longitudinal straight line C, extending along its top to which the face A is transverse. The handle D rises perpendicularly from the line C at a point much nearer the face A than the rear end of the head.

Having thus described my invention, I claim as new and desire to secure by Letters Patent—

The design for a golf-club substantially as herein shown and described.

In testimony whereof I have hereunto set my hand this 17th day of June, 1897.

JOHN HOWARD ADAMS.

In presence of—

HERMAN MEYER,
CLARENCE L. BURGER.
